DESIGN FOR A TEXTILE FABRIC

Herbert R. Shapiro, New York, N. Y.

Application December 12, 1939, Serial No. 88,839

Term of patent 3½ years

To all whom it may concern:

Be it known that I, Herbert R. Shapiro, a citizen of the United States of America, residing in the city of New York, county of New York and State of New York, have invented a new, original, and ornamental Design for a Textile Fabric, of which the following is a specification, reference being had to the accompanying drawing, forming part thereof.

The figure is a plan view of a textile fabric showing my new design. The dot and dash lines surround the design unit, which unit is repeated in regular succession as indicated by the extensions beyond the unit boundaries.

I claim:

The ornamental design for a textile fabric, substantially as shown and described.

HERBERT R. SHAPIRO.
